EXERCISER

Gerson Snyder, Philadelphia, Pa., assignor to Snyder Manufacturing Company, Philadelphia, Pa., a corporation of Pennsylvania

Filed Feb. 15, 1967, Ser. No. 5,831

Term of patent 7 years

(Cl. D34—5)

FIG. 1.

FIG. 4.

FIG. 2.

FIG. 3.

FIG. 1 is a view in perspective of an exerciser showing my new design the opposite side being substantially a mirror image thereof;

FIG. 2 is an enlarged fragmentary sectional view on line 2—2, FIG. 1;

FIG. 3 is an enlarged fragmentary sectional view on line 3—3, FIG. 1; and

FIG. 4 is an enlarged sectional view on line 4—4, FIG. 1.

I claim:

The ornamental design for an exerciser, substantially as shown and described.
